Primary Examiner — Robert M Spear*Assistant Examiner* — Kendra L Hamilton(74) *Attorney, Agent, or Firm* — Dunlap Bennett & Ludwig PLLC**CLAIM**

The ornamental design for a horseshoe, as shown and described.

DESCRIPTION

FIG. 1 is a perspective view of a horseshoe;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof; and,

FIG. 6 is a bottom plan view thereof.

The broken lines shown in the drawings illustrate portions of the horseshoe that form no part of the claimed design.
